LOADING DEVICE FOR TOP ROLLERS OF DRAWING MECHANISMS OF SPINNING MACHINES

Sigmund Kemmler, Geislingen, Steige, Wurttemberg, Germany, assignor to Wurttembergische Spindelfabrik G.m.b.H., Sussen, Wurttemberg, Germany

Filed July 24, 1961, Ser. No. 126,820

Claims priority, application Germany, Aug. 19, 1960, W 28,406

11 Claims. (Cl. 19—272)

The present invention relates to a loading or weighting device for the top rollers of drawing mechanisms of spinning machines, and more particularly to a magnetic loading device for such top rollers.

For loading the top rollers of drawing mechanisms of spinning machines it has already been proposed to magnetize these rollers, which are made of steel, so that the magnetic forces acting between them and the bottom rollers will produce the desired load thereon. This manner of loading the top rollers has been primarily applied to the slip rollers of slip-draft mechanisms in which the magnetization was intended to effect a retarding action upon the slip rollers in order to take up the angular momentum of these rollers. It has also been proposed to provide the top rollers with a core of a magnetically highly saturable alloy in order to produce a sufficient clamping pressure.

Since with such devices it must always be expected that the magnetic top rollers will also attract other metallic bodies, and since such rollers prevent the use of the conventional bearing means therefor because of the interference which they would cause in the magnetic flux, it has also already been proposed to provide each bearing saddle with a magnet at the side facing toward the respective bottom roller. Such an arrangement allows, however, very little space for the magnets, and the magnetic forces generated are therefore hardly sufficient to produce a clamping pressure of an adequate strength.

It is an object of the present invention to provide a magnetic loading or weighting device for the drawing mechanism of a spinning machine in which the magnets may be made of such a size that practically any desired loading pressure may be attained. This object is attained according to the invention by the provision of magnets for loading each top roller formed of two parallel arms and a magnetic block, by securing these magnets on the guide arms of the top rollers by means of special holders, by making the bearing members or bearing saddles for the top rollers of a nonmagnetizable material, and by mounting these bearings between the two arms of each magnet so as to be held or guided thereby. These bearings or saddles for the top rollers are preferably made of plastics.

The saddle-shaped bearings may be placed directly upon the shafts of the top twinrollers or the bearing members which are mounted between the arms of the magnets may be fitted upon the end journals of the top rollers. It is also possible to apply a combination of these arrangements, in which case each top twinroller is then loaded by three magnets. Each loading magnet or pair of magnets may be adjustably mounted on and secured to a separate arm which may be pivoted about an axis which lies within an arc the center of curvature of which lies within the axis of the respective bottom roller when the top roller is in the operative position. The loading magnets may, however, also be mounted on a common supporting arm and each of them may be pivotable on said arm about a pin or bolt which is adjustable within an arcuate slot. Especially if the magnets act upon the two end journals of each top roller, it is

2

possible according to the invention to guide the magnets relative to the respective bottom roller by means of simple bifurcated members of a nonmagnetic material, for example, of plastic. If the bearing members or saddles

5 between the magnet arms are designed so as to be adjustable in the direction of these arms, small differences in the thickness of the coatings or covers on the top rollers may be easily compensated so that the air gap between the magnet and the bottom roller and thus also the load 10 upon the latter will remain uniform. The bearing members or saddles may, however, also be similarly adjusted for varying the size of the air gap and for thus varying the force of the load. In order to facilitate the manipulation and servicing of the mechanism, the same may also 15 be designed so that, when the supporting arm or arms are pivoted upwardly, the individual top rollers will not be lifted simultaneously but will be successively lifted off of the bottom rollers. This considerably facilitates the interruption of the different magnetic circuits and also 20 permits a partial release of the drawing mechanism.

The aforementioned as well as additional objects, features, and advantages of the present invention will become more clearly apparent from the following detailed description thereof, particularly when the same is read 25 with reference to the accompanying drawings, in which—

FIGURE 1 shows a drawing mechanism with several supporting arms in a longitudinal section taken along line I—I of FIGURE 2;

FIGURE 2 shows a cross section taken along line 30 II—II of FIGURE 1;

FIGURE 3 shows a side view of a magnet which is fitted upon an end journal of a top roller;

FIGURE 4 shows a front view of a magnet according to FIGURE 3; while

35 FIGURE 5 shows a side view, partly in section, of a drawing mechanism with magnets mounted on a common supporting arm.

Referring first to FIGURES 1 and 2 of the drawings, the individual supporting or guide arms 1, 1' and 1" for the top twinrollers 2, 2', and 2" of the drawing mechanism carry magnet supports 3, 3', and 3" which are provided with arcuate dovetailed guide surfaces 4, 4', and 4", respectively. The centers of curvature of the arcs of guide surfaces 4, 4', and 4" coincide in the operative 45 position with the axes of the bottom rollers. It is thus possible to adjust the top rollers freely toward the front or rear relative to the bottom rollers without changing the distance of the pole faces from the bottom rollers.

The magnet supports 3, 3', and 3" carry magnet holders 5, 5', and 5" which may be clamped to the arcuate dovetailed guide surfaces 4, 4', and 4", respectively. The sides of the magnet holders facing toward the bottom rollers are also provided with dovetailed guides 7', as shown in FIGURE 2, which, however, are not curved 55 but straight. These guides 7' are adapted to receive magnet arms 8, 8', 8", and 9, 9', 9", respectively, the upper ends of which extending beyond the magnet blocks 10, 10', and 10" are slipped over the guides 7'. The magnets are locked to the magnet holders by means of shims 11, 11', and 11" which are secured by bolts 6, 6', and 6", respectively. The position of shims 11' has been 60 illustrated in FIGURE 2. Underneath the magnet blocks 10, 10', and 10", the nonmagnetic saddle-shaped bearings members 12, 12', and 12" for the shafts 13, 13', and 13" of the top rollers are mounted between the two arms of the respective magnets. Wedge gib 14, 14', and 14" which are slidable in a direction vertically to the magnet arms permit the bearings 12, 12', and 12" to be 65 adjusted by setscrews in the direction of the magnet arms, whereby the distance between the pole faces and the bottom rollers may be very accurately regulated. The low-

er ends of the magnet arms serving as pole pieces are bent inwardly so that in the operative position they extend substantially perpendicularly to the outer surface of the bottom rollers and their end surfaces or pole faces are separated from the bottom rollers only by narrow, 5 substantially parallel gaps.

The supporting arm 1 is provided with a projection 15 which, when arm 1 is pivoted upwardly for a certain distance about the fixed supporting rod 16, first takes along arm 1' and then also arm 1''. The forces produced by the three magnets may thus be overcome successively which facilitates the manipulation of the mechanism.

FIGURES 3 and 4 illustrate a modification of the invention as applied to individual top rollers or twin top 15 rollers, which have a journal 47 on each outer end. Each of these journals 47 of each top roller or twin top roller may be equipped with a magnet which consists of the magnet arms 38 and 39 and the magnet block 40 between these arms. The nonmagnetic bearing member 20 42 is slipped over journal 47 and it may be adjusted in a direction parallel to the magnet arms by the wedge gib 44 by means of a setscrew 48. A bifurcated member 34 which may consist, for example, of plastic, is firmly secured to the magnet by screws 49. If the lower 25 ends of the magnet arms 38 and 39 are disposed at the same distance from the bottom roller, the magnetic forces act symmetrically relative to the longitudinal axis of the magnet which also intersects with the axis of the top roller. The two arms of the bifurcated member 34 which surround the bottom roller are then not subjected to any lateral forces so that the friction between these two arms and the bottom roller is of no consequence, especially if member 34 is made of a plastic with 30 good bearing properties. The two arms of member 34 merely have to serve the purpose of insuring that the pole pieces, that is the lower ends of the magnet arms 38 and 39 remain equally spaced from the bottom roller.

FIGURE 5 illustrates a further modification of the invention in which a single main supporting arm 51 which is pivotable about the fixed supporting rod 66 is provided for the magnets of all three top rollers. Supporting arm 51 carries the magnet supports 53, 53', and 53'' which are slidably adjustable thereon. The magnet holders 55, 55', and 55'' are pivotable about pins or bolts 67, 67', and 67'' which, in turn, are slidable in arcuate slots 54, 54', and 54'' in the magnet holders to different positions in which they may be locked. Since in the operative position the center of curvature of each of these arcuate slots lies within the axis of the respective bottom 50 roller, it is possible to adjust each top roller forwardly or backwardly relative to the associated bottom roller by sliding the pivot pin or bolt 67 along slot 54.

Magnet holder 55 is provided with an extension 68 which serves as an operating handle. The supporting arm 51 further carries pawl-like brackets 69 and 69' which are adapted to hook over projections 70 and 70' on the magnet holders 55' and 55'', respectively, and are adjustable relative to magnet holders 55' and 55'' and their hook-shaped projections 70 and 70', respectively. The distance between the engageable surfaces of parts 69 and 70 is 55 preferably made smaller than the distance between the engageable surfaces of parts 69' and 70'. When the magnet holder 55 is pivoted upwardly by handle 68, the magnetic connection between the bottom delivery roller and the associated magnet will be interrupted. Magnet holder 55 will then be arrested in its upward position by a snap spring 72 on arm 51 which engages into a detent 71. In this manner it is possible to release and also to remove the top delivery roller without requiring the supporting arm 51 to be pivoted upwardly.

If arm 51 should be pivoted upwardly for cleaning, releasing, or removing any or all top rollers, magnet holder 55 is first pivoted by handle 68 until its detent 71 has snapped over spring 72. When handle 68 is then

further raised, magnet holder 55 takes along arm 51 and pivots the same about rod 66, whereby pawl 69 engages with hook 70, lifts the central magnet and top roller off the associated bottom roller, and thereby interrupts the magnetic circuit between these two rollers. Not until this has occurred during the continued upward movement of arm 51, will pawl 69' also engage with hook 70' and lift the last magnet and top roller off the associated bottom roller. The interruption of the different magnetic circuits therefore occurs successively and may thus be carried out without any great physical effort. If the distances between pawl 69 and the clamp 70 provided on the magnetic holder 55' is maintained considerably greater than the distance of pawls 69' from the clamp 70', then the magnetic flux of the pair of inlet rollers 52'', 62'' will initially be interrupted during the upward movement of arm 51, and only thereafter that of the central pair of rollers 52', 62'.

If arm 51 is pivoted upwardly directly and magnet holder 55 is not raised by handle 68, the feed roller or the central top roller or both may be released without affecting the load upon the delivery roller. However, the air gap of the magnet for the delivery roller then changes slightly so that the load is slightly decreased. Such a partial release of the load during which the yarn still remains clamped between the delivery rollers is sometimes desirable when the machine is to remain inoperative for a greater length of time, for example, for several days.

Although my invention has been illustrated and described with reference to the preferred embodiments thereof, I wish to have it understood that it is in no way limited to the details of such embodiments, but is capable of numerous modifications within the scope of the appended claims.

Having thus fully disclosed my invention, what I claim is:

1. A device for loading the top rollers of a drawing mechanism for a spinning machine comprising at least one pair of associated top and bottom rollers, at least a part of said bottom roller consisting of a magnetizable material, a supporting arm, means for pivotably mounting said supporting arm near one end, magnet means associated with said pair of top and bottom rollers, said magnet means including a pair of spaced magnet arms, means for securing one end of each magnet arm of said magnet means to said supporting arm, the other end of each of said magnet arms opposite said supporting arm being spaced by an air gap from said magnetizable part of said bottom roller, and a bearing member of a non-magnetizable material mounted between said magnet arms for rotatably mounting said top roller.

2. A device for loading the top rollers of a drawing mechanism for a spinning machine comprising a plurality of pairs of associated top and bottom rollers arranged separately from and behind each other in a row at least a part of each of said bottom rollers consisting of a magnetizable material, a plurality of supporting arms, means for pivotably mounting each supporting arm near one end thereof, magnet means associated with each respective pair of top and bottom rollers, each said magnet means including a pair of spaced, essentially parallel magnet arms and a magnet block secured between said magnet arms to maintain the same in spaced relationship, means for securing one end of each magnet arm of a respective magnet means to a respective supporting arm, the other ends of said magnet arms opposite said supporting arm being spaced by an air gap from said magnetizable part of each respective bottom roller, and a bearing member of non-magnetizable material mounted between said magnet arms of each magnet means for rotatably mounting said top rollers.

3. A device for loading the top rollers of a drawing mechanism for a spinning machine comprising at least one pair of associated top and bottom rollers, at least a

part of said bottom roller consisting of a magnetizable material, at least one supporting arm, means for pivotably mounting said supporting arm near one end thereof, magnet means associated with said pair of top and bottom rollers, said magnet means including a pair of spaced magnet arms, means for securing one end of each magnet arm of said magnet means to said supporting arm, the other ends of said magnet arms opposite said supporting arm being spaced by an air gap from said magnetizable part of said bottom roller, a bearing member of a non-magnetizable material mounted between said magnet arms for rotatably mounting said top roller, and means for adjusting the position of said bearing member in a direction parallel to said magnet arms.

4. A device for loading the top rollers of a drawing mechanism for a spinning machine comprising at least one pair of associated top and bottom rollers, at least a part of said bottom roller consisting of a magnetizable material, at least one supporting arm, means for pivotably mounting said supporting arm near one end thereof, magnet means associated with said pair of top and bottom rollers, said magnet means including a pair of spaced magnet arms, means for securing one end of each magnet arm of said magnet means to said supporting arm, the other ends of said magnet arms opposite said supporting arm being spaced by an air gap from said magnetizable part of said bottom roller, a bearing member of a non-magnetizable material mounted between said magnet arms for rotatably mounting said top roller, said bearing member having a surface inclined to said magnet arms, a wedge-shaped member between said magnet arms engaging with said inclined surface, and means for adjusting said wedge-shaped member in a direction substantially at right angles to said magnet arms for adjusting the position of said bearing member in a direction parallel to said magnet arms.

5. A device for loading the top rollers of a drawing mechanism for a spinning machine comprising at least one pair of associated top and bottom rollers, at least a part of said bottom roller consisting of a magnetizable material, at least one supporting arm, means for pivotably mounting said supporting arm near one end thereof, magnet means associated with said pair of top and bottom rollers, said magnet means including a pair of spaced magnet arms, means for securing one end of each magnet arm of said magnet means to said supporting arm, the other ends of said magnet arms opposite said supporting arms being bent toward each other and their end surfaces spaced by an air gap from the peripheral surface of said magnetizable part of said bottom roller, a bearing member of a non-magnetizable material mounted between said magnet arms for rotatably mounting said top roller, and means for adjusting the position of said bearing member in a direction parallel to said magnet arms.

6. A device for loading the top rollers of a drawing mechanism for a spinning machine comprising at least one pair of associated top and bottom rollers, at least a part of said bottom roller consisting of a magnetizable material, at least one supporting arm, means for pivotably mounting said supporting arm near one end thereof, magnet means associated with said pair of top and bottom rollers, said magnet means including a pair of spaced magnet arms, means for securing one end of each magnet arm of said magnet means to said supporting arm, the other ends of said magnet arms opposite said supporting arm being spaced by an air gap from said magnetizable part of said bottom roller, a bearing member of a non-magnetizable material mounted between said magnet arms for rotatably mounting said top roller, means for adjusting the position of said bearing member in a direction parallel to said magnet arms, and a bifurcated member of a non-magnetizable material mounted on said magnet arms and having a pair of guide arms, said magnetizable part of said bottom roller being disposed between said guide arms

and in slidable engagement therewith for maintaining the open ends of said magnet arms at an equal distance from said magnetizable part of said bottom roller.

7. A device for loading the top rollers of a drawing mechanism for a spinning machine comprising a plurality of pairs of associated top and bottom rollers arranged separately from and behind each other in a row, at least a part of each of said bottom rollers consisting of a magnetizable material, each of said top rollers being formed by twin rollers and a shaft portion interconnecting said rollers, a plurality of supporting arms, means for pivotably mounting each supporting arm near one end thereof, magnet means associated with each pair of top and bottom rollers, each said magnet means including a pair of spaced magnet arms, means for securing one end of each magnet arm of a respective magnet means to a respective supporting arm, the other end of said magnet arms opposite said supporting arm being spaced by an air gap from said magnetizable part of each respective bottom roller, and a bearing member of a non-magnetizable material mounted between said magnet arms of each magnet means for rotatably mounting said shaft portion of each of said top rollers.

8. A device for loading the top rollers of a drawing mechanism as defined in claim 6, wherein said top roller includes a journal at each end thereof, and said bearing member is associated with said journal, said bearing member being slipped over a respective journal.

9. A device for loading the top rollers of a drawing mechanism for a spinning machine comprising a plurality of pairs of associated top and bottom rollers arranged separately from and behind each other in a row, at least a part of each of said bottom rollers consisting of a magnetizable material, a separate supporting arm for each of said top rollers, means for mounting said supporting arms near one end for a separate pivoting movement about a common axis, at least one magnet means associated with each pair of top and bottom rollers, each said magnet means including a pair of spaced magnet arms, means for securing one end of each magnet arm for a respective magnet means to a respective supporting arm and for adjusting said respective magnet means to different positions along the length of said supporting arm, the other ends of said magnet arms opposite said supporting arm being spaced by an air gap from said magnetizable part of said bottom roller, and a bearing member of a nonmagnetizable material mounted between said magnet arms for rotatably mounting said top roller.

10. A device for loading the top rollers of a drawing mechanism for a spinning machine comprising a plurality of pairs of associated top and bottom rollers arranged separately from and behind each other in a row, at least a part of each of said bottom rollers consisting of a magnetizable material, a separate supporting arm for each of said top rollers, means for mounting said supporting arms near one end for a separate pivoting movement about a common axis, said supporting arms being disposed one above the other and being of different lengths, means on the uppermost supporting arm adapted to engage successively with and take along the other supporting arms when said uppermost arm is pivoted upwardly, at least one magnet means associated with each pair of top and bottom rollers, each said magnet means including a pair of spaced magnet arms, means for securing one end of each magnet arm for a respective magnet means to a respective supporting arm and for adjusting said respective magnet means to different positions along the length of said supporting arm, the other ends of said magnet arms for said respective magnet means opposite said supporting arm being spaced by an air gap from said magnetizable part of said bottom roller, and a bearing member of a nonmagnetizable material mounted between said magnet arms for rotatably mounting said top roller.

11. A device for loading the top roller of a drawing

mechanism for a spinning machine comprising a plurality of pairs of associated top and bottom rollers arranged separately from and behind each other in a row, at least a part of each of said bottom rollers consisting of a magnetizable material, a common supporting arm for all of said top rollers, means for pivotably mounting said supporting arm near one end, magnet means associated with each pair of top and bottom rollers, each said magnet means including a pair of spaced magnet arms, means for connecting one end of each magnet arm of the respective magnet means to said supporting arm and for adjusting the respective magnet means to different positions along the length of said supporting arm and for securing said magnet means to said supporting arm in the adjusted positions, the other ends of said magnet arms for the respective magnet means opposite the supporting arm being

spaced by an air gap from said magnetizable part of the associated bottom roller, a bearing member of a non-magnetizable material mounted between said magnet arms for rotatably mounting one of said top rollers, and means for adjusting the position of said bearing member in a direction parallel to said magnet arms.
